ADJUSTABLE FASTENER

Filed Feb. 27, 1929

ATTORNEYS.

UNITED STATES PATENT OFFICE

MONES GROSS, OF POTTSVILLE, PENNSYLVANIA

ADJUSTABLE FASTENER

Application filed February 27, 1929. Serial No. 343,160.

The present invention relates to improvements in adjustable fasteners, and more specifically to improvements in means for adjustably connecting the ends of a belt or 5 the like such as employed for supporting trousers and other garments.

The primary object of the invention is to provide an adjustable fastener for belts which will allow for the loop or free end of the 10 belt to be concealed and thus provide a smooth outer surface at each side of the fastener for improving the appearance of the belt.

A further object of the invention is to provide an adjustable belt fastener of such 15 construction as to eliminate the use of loops for receiving the loose end of the belt, and also dispense with the showing of rivets or other fastening elements on the outer surface of the belt.

20 A further object of the invention resides in the provision of an adjustable belt fastener which will allow for more economical handling of the belts for sale, in that less belt sizes need be carried in stock owing to the fact 25 that the loose end of the belt when being worn will be disposed in a concealed position inwardly of the belt and therefore may extend for any distance beyond the fastener and need not necessarily be of such length as to 30 properly engage in loops for properly holding the loose end in overlying relation to the belt.

Still further objects of the invention are 35 to provide a device of this character which may be economically constructed from sheet metal stampings, one wherein the length of the belt may be readily and quickly adjusted, and one wherein the terminal of the normally 40 attached end of the belt is reinforced at its point of detachable connection with the buckle proper of the fastener.

Other objects and advantages of the invention will be apparent during the course 45 of the following detailed description, taken in connection with the accompanying drawing forming a part of this specification and in which drawing:

Figure 1 is a central longitudinal section thru the improved fastener shown adjustably 50 connecting opposite ends of a belt.

Figure 2 is a front plan view of the fastener on a reduced scale from that shown in Figure 1 and showing portions of the fastener broken away for illustrating the manner in which the fastener is detachably connected 55 with the butt end of the belt.

Figure 3 is a perspective view of the inner side of the buckle portion of the fastener.

Figure 4 is a side elevation of the buckle and showing portions broken away for illustrating the manner in which the gripper is 60 mounted.

Figure 5 is a plan view of the blank from which the body portion of the buckle is 65 formed.

Figure 6 is a plan view of the blank form from which the head piece or cap for reinforcing the butt end of the belt may be formed.

In the drawings, and wherein similar reference characters designate corresponding parts thruout the several views, the improved fastener has been shown adapted for use in adjustably connecting the ends of a flexible belt such as worn about the waist of a person 70 for supporting trousers or the like. The letter A may designate the flexible belt which may be of leather or any other suitable material having its ends adjustably connected by the improved fastener B. For the purpose of explanation the belt A may be considered as having a butt or head end 5 and a loose or free end 6, while the adjustable fastener B includes a reinforcing head piece or 75 cap 7 and a buckle 8 for detachable connection with the butt end 5 of the belt and adjustably receiving the free end 6.

Referring first to the specific construction of the head piece or cap 7 serving as a reinforcement for the butt end 5 of the belt, the 80 same is preferably formed from a sheet metal stamping clamped over the butt end of the belt in such manner as to be entirely concealed by the buckle 8. The butt end of the belt is provided with a transverse slot 9 85 which terminates inwardly of the upper and lower edges of the belt, and this slot forms an opening into which the tongue on the buckle 8 projects for detachably coupling the buckle to one end of the belt. The head piece 90

7 and which may be formed from any suitable sheet metal, is bent along the line 10 in Figure 6 to form inner and outer plate sections 11 and 12 respectively which are clamped over the butt end of the belt. The outer plate section 12 is relatively narrow and overlies only a small portion of the outer surface of the belt beyond the slot 9, and this outer plate section is provided along its free side edge with an elongated tongue 13 which is bent inwardly into the slot 9. The inner plate section 11 is of greater length than the outer plate section 12 and has struck from its intermediate portion a tongue 13' which is bent forwardly into the slot 9 whereby the tongues 13 and 13' aside from clamping the cap to the belt also provide a reinforcement along the forward edge of the slot 9. Provided at the upper and lower edges of the inner plate section, rearwardly of the tongue 13, are triangular shaped extensions 14 which are intended to bite into the belt along its upper and lower edges intermediate the inner and outer surfaces of the belt so that the cap 7 is firmly anchored to the butt end of the belt inwardly of the slot 9. As will be observed in Figure 2, the head or cap 7 is of a height substantially equal to the width of the belt.

Referring now to the specific construction of the buckle 8, the same includes a frame 15 which is preferably formed from a single blank sheet of the configuration illustrated in Figure 5. The frame 15 includes a longitudinally arcuated face plate 16 and a clamp plate 17 bent to extend in overlying relation at the inner side of the face plate 16. The clamp plate 17 has a reduced end portion 18 which is bent substantially at a right angle along the line 19 toward the face plate 16 for providing a tongue 20 having rounded ends and having its free end engaging the rear surface of the face plate inwardly of the forward edge 21. The clamp plate 17 for a portion of its length is in contact with the rear surface of the face plate 16 and the tongue 20 by its engagement with the face plate provides a pocket 22 for receiving the butt end of the belt A when the tongue 20 is engaging in the slot 9.

Formed along each side edge of the face plate 16 is an extension 23 and which extensions are intended to be bent inwardly in spaced relation over the rear side of the face plate to provide guide ways 24 having their ends terminating inwardly of the ends of the frame and which guideways receive the loose end 6 of the belt. The rear end of each elongated extension or flange 23 is curled inwardly to provide elongated loops 25 forming pivotal mountings for a keeper 26.

The keeper 26 for pivotal mounting between the elongated loops 25 embodies an elongated head piece 30 having trunnions 31 at each end for fitting in the elongated open-

ings formed by the loops 25. Extending from the head piece 30 is a bail-like handle 32 which extends in overlying relation to the clamp plate 17 between the flanges 23. As will be observed in Figures 1 and 4, the trunnions 31 extend from the ends of the head piece 30 at a location adjacent the rear edge 33 of the head piece so that when the bail 32 is swung upwardly the loose end of the belt will have free sliding movement between the edge 33 and inner surface of the arcuated clamp plate 17. The forward face of the head piece 30 is longitudinally corrugated to provide a gripping face 34 which bites into the belt material and prevents possible slipping of the belt out of the buckle. The bail 32 is offset intermediate its ends as clearly shown in Figure 1 and conforms substantially to the shape of the free end portion of the clamp plate 17 with the free end of the bail extending to a point relatively near the tongue 20. The bail 32 engages the loose end 6 of the belt and tendency of the loose end to be withdrawn from the buckle will cause the bail to be more firmly pressed against the belt and by reason of the bail extending to a location relatively near the tongue 20 the pressure exerted on the belt by the bail will act to more firmly retain the tongue 20 in the slot 9.

The material from which the frame 15 is formed is preferably of a nature so that the clamp plate 17 will be yieldable and have sufficient spring tension to normally retain the tongue 20 in engagement with the face plate 16. While the clamp plate 17 has been shown formed integral with the face plate 16 it is to be understood that if so desired the clamp plate may be formed of suitable spring material and affixed in any suitable manner at one end to the rear side of the face plate 16 as when it is desirable that the face plate be formed of such material as would prevent making of the clamp plate of the same material as that of the face plate. In the example illustrated the face plate 16 has been shown provided with a suitable plating 40.

In use of the improved fastener the clamp plate 17 may first be sprung for allowing the tongue 20 to be positioned in the slot 9 whereby the buckle is detachably coupled to one end of the belt. The head piece or cap 7 as will readily be apparent so reinforces the butt end of the belt as to prevent likelihood of the tongue 20 severing a portion of the belt beyond the slot 9. With the keeper 26 then swung to an open position by raising the bail 32, the free end 6 of the belt is fed between the keeper head piece 30 and rear surface of the clamp plate 17 for the desired distance for contracting the belt about the wearer's waist, and then upon moving the bail 32 toward the belt the gripping face 34 so engages

the belt as to prevent movement of the free end of the belt out of the buckle.

By having the tongue 20 engage the face plate inwardly of the forward edge it will be seen that the slot 9 is covered by the face plate. The cap 7 is also concealed by the face plate and by having the inner cap plate section 11 anchored in the upper and lower edges of the belt material the cap is concealed at this point and is firmly anchored to the belt without having exposed rivets or the like.

In Figure 1 it will be seen that this novel arrangement allows for the loose end 6 of the belt to be disposed inwardly of the butt end 5 and thus the length of the loose end 6 may project for any distance beyond the fastener without detracting from the appearance of the belt.

Changes in the shape, size and arrangement of parts may be made to the form of invention herein shown and described, without departing from the spirit of the invention or the scope of the following claims.

I claim:

1. In a buckle of the class described a frame including a face plate, a clamp plate connected at one end with one end of the face plate and extending over the rear side of the face plate, said clamp plate at its opposite end having a forwardly bent tongue having its free edge engageable with the inner surface of the face plate and providing a pocket for releasably receiving the butt end portion of the belt, rearwardly directed flanges formed along the upper and lower edges of the face plate, each flange having its end adjacent the first mentioned end of the face plate provided with loops, and a keeper including a head piece pivotally mounted in the loops and a lever portion extending forwardly between the flanges, said head piece having gripping engagement with the free end of a belt inserted between it and the rear surface of the clamp plate and said lever portion adapted to engage the free end of the belt for normally urging the same into frictional contact with the tongue end of the clamp plate.

2. In a buckle of the class described, a one piece frame including a face plate, a clamp plate bent inwardly from one end of the face plate with a portion of its length in surface contact with the rear surface of the face plate, a tongue bent forwardly from the free end of the clamp plate at the rear side of the face plate, a flange bent inwardly and rearwardly from the upper and lower edges of the face plate and providing confronting guide ways for receiving the free end of a belt, said flanges each having a loop formed at its rear end, and a keeper including a head piece pivotally mounted at each end in the loops and a lever extending between the flanges with its free end terminating at a location

adjacent the free end of the clamp plate, said keeper when swung to an open position allowing for the free end of the belt to be inserted beneath the keeper head portion and extended over the inner surface of the clamp plate to project inwardly of the butt end of the belt with which the tongue of the clamp plate has detachable connection.

3. In an adjustable fastener for belts, a buckle comprising a one-piece frame including a face plate, a yieldable clamp plate bent inwardly over the rear side of the face plate from one end thereof, and flanges formed along the upper and lower edges of the face plate, said clamp plate having a tongue at its forward end in engagement with the rear side of the face plate adjacent the opposite end thereof for detachably coupling the buckle to the butt end of the belt, and a keeper pivotally mounted in the flanges at the first mentioned end thereof for gripping engagement with the free end of the belt for releasably retaining the same in frictional contact with the inner surface of the clamp plate.

4. In a buckle of the class described, a one-piece frame including a face plate, a clamp plate bent inwardly from one end of the face plate with a portion of its length in surface contact with the rear surface of the face plate, a tongue bent forwardly from the free end of the clamp plate into engagement with the rear surface of the face plate, and rearwardly bent flanges along the upper and lower edges of the face plate and having their forward ends terminating rearwardly of said tongue, and a keeper mounted between the rear ends of the flanges for gripping engagement with the free end of the belt.

5. In a belt buckle, an elongated face plate, guide forming flanges provided along the upper and lower longitudinal edges of the face plate, a yieldable arcuate clamp plate carried by and arranged at the rear side of the face plate between the guide flanges and extending through the major portion of the length of the face plate, for detachable connection at its one end with the butt end of the belt, and a keeper pivotally mounted between the guide flanges adjacent the other end of the clamp plate for frictionally clamping the free end of the belt in surface contact with the inner surface of the arcuate clamp plate.
